UNITED STATES PATENT OFFICE.

JOHN H. BURPEE, OF BELLINGHAM, WASHINGTON, ASSIGNOR OF ONE-HALF TO
EUGENE T. HOSKINS, OF BELLINGHAM, WASHINGTON.

MOLDING-MACHINE.

1,073,210.

Specification of Letters Patent. Patented Sept. 16, 1913.

Application filed November 4, 1912. Serial No. 729,187.

To all whom it may concern:

Be it known that I, JOHN H. BURPEE, a subject of the King of Great Britain, and a resident of the city of Bellingham, in the 5 county of Whatcom and State of Washington, have invented certain new and useful Improvements in Molding-Machines, of which the following is a specification.

My invention relates to apparatus for 10 packing sand or similar material about patterns in molds and aims primarily to provide an apparatus of this character wherein the packing member is mounted for operation in a novel manner.

Further, the invention resides in the provision of novel means for supporting the mold in a manner insuring of the sand being more firmly and uniformly packed by the packing member.

With the above and other objects in view 20 to be referred to as my description progresses my invention resides in the features of construction, arrangements and combinations of parts hereinafter described and succinctly defined in my annexed claims.

Referring to the accompanying drawings wherein like numerals of reference indicate like parts throughout: Figure 1 is a side elevation of the machine, parts being broken 30 away. Fig. 2 is a top plan thereof with portions broken away. Fig. 3 is an end elevation, a portion of the packing member or roll being broken away, and Fig. 4 is a vertical cross-section taken on line 4—4 of Fig. 2.

Referring to the drawings by numerals of reference, 1 indicates the packing member or roll, the same being formed of annular sections arranged end to end and rotatably mounted on a shaft 2 mounted on a 40 carrier 3 and having its projecting end portions received in guide ways 4 of standards 5.

The bores of the component sections of 45 roll 1 are of greater diameter than shaft 2, by which construction the several roll sections are free of the shaft and one another for limited relative movement, thereby enabling the same to have their weight so imposed on the sand as to insure a more perfect packing action.

Standards 5 are fixed to a base or bed 6, conveniently supported by legs 7, and have 50 their upper end portions united by a cross beam 8, on which latter I journal a drum 9

which drum is connected by a flexible connection, or cable 10 to carrier 3.

Fixed to the shaft of drum 9 is a worm wheel 11 with which meshes a worm 12, fixed to a drive shaft 13, journaled in stands 60 14, and provided with a fixed sprocket wheel 15 and a normally loose pulley 16, which latter is adapted to be driven by a belt, not shown.

Reference numeral 17 indicates a clutch 65 part splined to shaft 13 and adapted to be moved by a suitable lever, as 18, into and out of engagement with a clutch part 17' of pulley 16.

Reference numeral 19 indicates a hand 70 wheel, journaled on a stub shaft of one of the standards 5, and provided with a sprocket wheel 20, taking over which and said sprocket wheel 15, is a chain 21.

With clutch parts 17 and 17' engaged, 75 pulley 16 transmits power to shaft 13 to elevate roll 1, and when the latter is sufficiently elevated and the clutch opened, it will be held by worm wheel 11 and worm 12 against accidental lowering in its adjusted 80 position which can be varied in a downward direction manually through operation of hand wheel 19.

Reference numeral 22 indicates an endless 85 conveyer on which a mold, as 23, is placed and fed beneath roll 1.

Conveyer 22 which conveniently comprises a plurality of endless belts arranged side by side and taking over broad sprocket wheels on drive and driven shafts 24 and 25 90 respectively, has its upper run extending over and slightly elevated from bed or base 6. At a point directly beneath roll 1, bed or base 6 is cut out, as at 6', and through this cut-out an idler roller 26 projects sufficiently above the bed or base to support the upper run of the conveyer and prevent undue friction between the latter and bed or base 6 incident to the passage of mold 23 beneath roll 1 during the packing operation. 100

Drive shaft 24 is provided with a friction wheel 27 adapted to be driven by a friction driver 28 fixed to a shaft 29, provided with a pulley 30 over which a belt, not shown, takes. Shaft 29 is journaled in a slide bearing 30' which is conveniently guided in a guide way 31, provided on the under face of bed or base 6, and connected by a link 32 with a bell crank lever 33 which in turn is connected by a link 34 with a treadle 35. 110

In operation, following the placement of the mold 23 on conveyer 22, roll 1 is lowered into operative position for packing, through proper manipulation of hand wheel 19, following which, the operator applies his foot to treadle 35 to advance and hold driver 28 against friction wheel 27.

Having thus described my invention what I claim as new, and desire to secure by Letters Patent of the United States of America, is:-

1. In apparatus of the character described, means for supporting a mold substantially horizontally, a vertical guide means, and a sand packing roll supported for rotation and guided in said guide means for movement toward and from said first means, said roll being composed of a plurality of annular sections arranged end to end and free for relative movement toward and from said first means through resistance offered to them by the material in the mold during a packing operation.

2. In apparatus of the character described, means for supporting a mold, a shaft, means supporting said shaft at the side of said first means, and a roll on said shaft having a bore of relatively greater diameter than that of the shaft whereby it is free of the latter for independent movement in a direction away from said first means.

3. In apparatus of the character described, means for supporting a mold, a carrier guided for movement toward and from said first means, flexible means connected with said carrier for elevating the same, a shaft on said carrier, a packing roll mounted on said shaft, said roll being composed of a plurality of annular sections arranged end to end and having bores of relatively greater diameter than that of said shaft, whereby they are free of one another and said shaft for relative movement in a direction away from said first means.

4. In apparatus of the character described, means for supporting a mold, a vertically arranged guide projecting above said means, a packing roll, a carrier for said roll slidably engaged with said guide, a drum, a flexible connection between said drum and said carrier, and means for driving said drum comprising a worm and worm wheel in mesh.

5. In apparatus of the character described, means for supporting a mold, a vertically arranged guide projecting above said means, a packing roll, a carrier for said roll slidably engaged with said guide, a drum, a flexible connection between said drum and said carrier, a worm wheel connected to said drum, a drive shaft, a worm on said shaft in mesh with said worm wheel, and means for operating said shaft.

6. In apparatus of the character de-

scribed, means for supporting a mold, a sand packing roll supported for movement toward and from said means, and a shaft extending through said roll and rotatably supporting the same, the bore of said roll being of relatively greater diameter than that of the shaft whereby it is free of the latter for relative movement toward and from said means.

7. In apparatus of the character described, means for supporting a mold, a carrier supported for movement toward and from said means, a shaft on said carrier, and a roll rotatably mounted on said shaft, said roll being formed of a plurality of annular sections arranged end to end and having bores of relatively greater diameter than said shaft, whereby said roll sections are free of one another and said shaft for relative movement toward and from said means.

8. In apparatus of the character described, a support for a mold and a packing roll one of which is movable in a direction crosswisely of the other, said roll being composed of a plurality of annular sections, and means supporting said roll sections for movement independently of one another away from said support through resistance of the material being pressed during the packing operation.

9. In apparatus of the character described, means for supporting a mold substantially horizontal, a vertical guide means extending upwardly from said first means, and a sand packing roll guided in said guide means and normally free therein for movement from said first means through resistance of the material being pressed during a packing operation.

10. In apparatus of the character described, means for supporting a mold substantially horizontal, a vertical guide means extending upwardly from said first means, a sand packing roll guided in said guide means and normally free therein for movement from said first means through resistance of the material being pressed during a packing operation, and means for holding said roll against lowering from a predetermined elevation including a flexible connection permitting of the roll raising from such elevation during the operation of packing.

11. In apparatus of the character described, means for supporting a mold, a vertically movable supporting means, a flexible connection for holding said supporting means against lowering from a predetermined elevation, and a packing roll rotatably mounted on said supporting means and free thereof for relative movement away from said first named means.

12. In apparatus of the character described, means for supporting a mold, a

vertically movable supporting means, a guide for said supporting means, a flexible connection for holding said supporting means against lowering from a predetermined elevation, means connected with said flexible connection for raising said supporting means, and a packing roll rotatably mounted on said supporting means and free

thereof for relative movement away from said first named means.

Signed at Bellingham, Wash. this 22nd day of October 1912.

JOHN H. BURPEE.
